Primary Examiner — George J Ulsh*Assistant Examiner* — Andrea Marie McKay(57) **CLAIM**

The ornamental design for a portable camping fan, as shown and described.

DESCRIPTION

FIG. 1 is a right-front perspective view of a portable camping fan, showing my new design;

FIG. 2 is a left-rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged detail view of area 9 circumscribed in FIG. 1;

FIG. 10 is an enlarged detail view of area 10 circumscribed in FIG. 2; and,

FIG. 11 is an enlarged detail view of area 11 circumscribed in FIG. 4.

The broken lines depict portions of the portable camping fan that form no part of the claim. The dotted lines denote the boundaries of the detail areas and form no part of the claimed design.
